US0D1045283S

(12) **United States Design Patent** (10) Patent No.: **US D1,045,283 S**
(45) Date of Patent: ** Oct. 1, 2024

(54) **RECONFIGURABLE COMBINED TOILET PLUNGER, BRUSH, AND CADDY**

(71) Applicant: **Unger Marketing International, LLC**, Bridgeport, CT (US)

(72) Inventors: **James Buckley**, New Hartford, CT (US); **Brandon M. Temple**, Stamford, CT (US); **Stephen Huda**, Shelton, CT (US)

(73) Assignee: **Unger Marketing International, LLC**, Bridgeport, CT (US)

(**) Term: **15 Years**

(21) Appl. No.: **29/905,645**

(22) Filed: **Oct. 24, 2023**

(57) CLAIM

The ornamental design for a reconfigurable combined toilet plunger, brush, and caddy, as shown and described.

DESCRIPTION

FIG. 1 is a top-down perspective view of a reconfigurable combined toilet plunger, brush, and caddy in accordance with an embodiment;

FIG. 2 is a front elevation view of the embodiment shown in FIG. 1;

FIG. 3 is a rear elevation view of the embodiment shown in FIG. 1;

FIG. 4 is a right side elevation view of the embodiment shown in FIG. 1;

FIG. 5 is a left-side elevation view of the embodiment shown in FIG. 1;

FIG. 6 is a top-down plan view of the embodiment shown in FIG. 1;

FIG. 7 is a bottom-up plan view of the embodiment shown in FIG. 1;

FIG. 8 is top-down perspective view of the cleaning implement assembly of FIG. 1, illustrating a second orientation of the components thereof;

FIG. 9 is top-down perspective view of the cleaning implement assembly of FIG. 1, illustrating a third orientation of the components thereof;

FIG. 10 is top-down perspective view of the cleaning implement assembly of FIG. 1, illustrating a fourth orientation of the components thereof; and,

FIG. 11 is top-down perspective view of the cleaning implement assembly of FIG. 1, illustrating a fifth orientation of the components thereof.

The broken lines shown in the figures are for the purpose of illustrating portions of the reconfigurable combined toilet plunger, brush, and caddy and form no part of the claimed design.

The “UNGER” shown in dashed line and forming part of the design disclosure is a registered trademark, of Unger Marketing International, LLC, and forms no part of the claimed design.
